2 SHEETS—SHEET 1.

Fig. 1.

FIG. 2.

A technical drawing of a device. The top portion is a rectangular frame with diagonal hatching. A horizontal line with a break in the middle passes through the center of the frame. At the bottom center, there is a circular component labeled '13' with a vertical line extending downwards. A vertical line labeled '16' extends downwards from the bottom of the circular component. A horizontal line labeled '14' extends to the left from the bottom of the circular component. A vertical line labeled '11' extends upwards from the bottom of the circular component. A horizontal line labeled '12' extends to the right from the bottom of the circular component. A horizontal line labeled '17' extends downwards from the bottom of the circular component.

UNITED STATES PATENT OFFICE.

ORAN OLSON, OF HAUGEN, WISCONSIN.

WIRE FASTENER.

1,405,715.

Specification of Letters Patent. Patented Feb. 7, 1922.

Application filed August 27, 1919. Serial No. 320,257.

To all whom it may concern:

Be it known that I, ORAN OLSON, a citizen of the United States, residing at Haugen, in the county of Barron and State of Wisconsin, have invented certain new and useful Improvements in a Wire Fastener, of which the following is a specification.

This invention relates in general to fence construction and more particularly to a device which is adapted to facilitate the securing of strands of wire or mesh as may be desired or necessary to a fence post.

Another object of this invention is the production of a wire fastener whereby strands of wire mesh may be connected to the post, the securing means also acting as a reinforcement for the post, if desired, if the same be of a plastic construction.

Another object of this invention is the production of a wire fastener for plastic fence posts which is embedded within the post body to reinforce the same and projects forwardly therefrom through a central channel to allow wire strands or mesh to be positioned thereon and secured thereto by twisted loops engaging the several elements.

Two practical forms of construction and assembly of the present invention will be hereinafter described and are illustrated in the drawings, in which:—

Figure 1 is a front elevation of the wire fastener, as constructed in accordance with the present invention.

Fig. 2 is a horizontal section taken on the line 2—2 of Fig. 1.

Fig. 3 is a detail perspective view of the manner in which a twisted loop is employed for connecting the fence wire to the supporting means mounted upon the post.

Fig. 4 is a fragmentary vertical section through a portion of the device.

Fig. 5 is a front elevation of a slightly modified form of the invention.

Fig. 6 is a horizontal section taken on the line 6—6 of Fig. 5.

Fig. 7 is a vertical section of the device as illustrated in Fig. 5.

Fig. 8 is a front elevation of the device with the plastic fence post body removed.

In the preferred embodiment of the present invention about to be specifically described, it will be seen that 10 designates the plastic body of the post which may be of rectangular shape in cross section or any other desired configuration without departing at all from the spirit of the present invention.

This body 10 is provided with a vertically extending substantially semi-circular channel 11 in its forward surface as shown clearly in the drawings. It will be seen that the construction thus far presented is common to both forms of the invention as will be seen.

Attention is now invited to Figs. 1 to 4 inclusive, wherein one particular form of securing means for the wire fence strand is disclosed. An ordinary strip 12 of the common woven wire mesh, as illustrated clearly in Fig. 1 is embedded within the body 10 when the same is being formed within a mold, with a portion of the wire mesh 12 being pulled forwardly in a substantially U-shaped manner to form the mesh rib 13 positioned centrally within the channel 11 as shown in Figs. 2 and 4. As above stated, this wire mesh 12 is of the general type used for chicken runs, et cetera, and thus there is provided a plurality of loop like portions in the rib 13 as shown in Figs. 1 and 4. Accordingly the main supporting key 14 extends vertically within the forward portion of the channel 11 being threaded through the different loop like portions as shown clearly in Fig. 1 and thus it will be seen that it is firmly supported by the mesh rib 13. As it is at the forward portion of the channel it is in convenient position for use as will be further explained. The device as constructed as above set forth is inserted in the ground with the mesh rib 13 above the ground and in position for supporting the key 14 in position where access may be conveniently had thereto.

At this time the strands of wire 15 of the fence although of course, it could be wire mesh, are extended horizontally across the forward portion of the body and are extended across the forward portion of the rib and contacted with parts of the key 14. Loops 16 are then employed to retain the strands in position or rather in fixed engagement with the keys 14. These loops are formed from single strands of wires as shown clearly in Figs. 2 and 3, each of which is bent intermediate its ends to form a loop which is passed around a strand 15 and then in the rear of the key 14 and then around forwardly of the strand 15 where it is twisted together as tight as may be desired as shown at 17. Thus it will be seen that when the device is in use the wire strands 15 of the fence may be passed across the forward portions of the key 14 and then the retaining loops may be passed quickly about the strands 15 and key 14 being

twisted as specified, thus firmly securing the strands 15 upon the key. In the engagement of the loops it is obvious they will also engage about parts of the wire loop like portions of 5 the mesh rib 13 as illustrated in Fig. 1 whereby by the mesh rib, the key and the strands 15 will all be connected together in a very firm engagement with each other. Thus it will be seen that the connection is very cheap and 10 efficient and the fence wires will be firmly held upon the rib and key by the loops as specified, the mesh being held by the body portion of the wire mesh which is at this time embedded within the hard plastic body 10.

15 By referring to Figs. 5 to 8 inclusive it will be seen that a slightly different form of securement is provided. In this form of the invention the usual plastic body 10 having the vertical semi-circular channel 11 in 20 its forward surface is still employed but in this instance the strip of wire mesh is shown at 18 and extends transversely within the body 10 to reinforce the same. By referring to Figs. 5 and 6 it will be seen that the strip 25 of mesh 18, the construction of which is clearly illustrated in Fig. 8 may be extended transversely of the plastic body 10 or it may be bent around within the plastic body in any manner desired to reinforce the same.

30 The vertically extending key 19 is positioned in the rear of the mesh strip 18 and this key 19 has a plurality of securing yokes 20 extending forwardly beyond the mesh strip 18 and outwardly to the forward portion 35 of the channel 11 as shown in Figs. 6 and 7. Therefore, after the body 10 has become hardened and is inserted into the ground in the usual manner, the only portion of the securing means exposed to view 40 are the forward portions of the yokes, which at this time are in position for convenient access thereto. The strands 15 may be extended forwardly of the body and may then be connected to the yokes 20 by loops 16 45 which are passed about the strands 15 and through the yokes 20 to have their ends twisted together in the usual manner at 17 thus firmly connecting the strands to the yokes. It will be seen that as the yokes are 50 formed of a single strand of wire in each instance and as the loops are also formed of wire, the twisted end portions 17 may be so firmly twisted together as will tend to slightly bend the yokes and the loops and 55 even the strands 15 to connect the same very firmly together and preventing any tendency of accidental creeping of the strands 15 or displacement of any of these elements.

In the construction of the device in each 60 instance, when the plastic material is poured into a mold, the woven wire mesh strip either 12 or 18 is inserted into this plastic material with the rib 13 of one form extended forwardly into the channel 11 while 65 the other form of the key 19 is inserted into

the plastic material in the rear of the strip 18 so that the yokes extend forwardly into the channel. When the devices are in use it is evident the strands 15 of the wire fence or mesh as may be desired may be extended 70 forwardly across the forward surface of the post body to allow same to engage either the key 14 or the yokes 20 of key 19. The retaining loops 16 may then be passed about the strands and the keys or yokes as stated 75 and have their ends twisted together to firmly bind the strands in position. Thus the device as described in each instance will not only allow the wire strands of the post to be easily connected thereto and after being connected retained in a firm position but the strips of mesh which facilitate the retention of the keys to which the strands are connected also act as reinforcements of a 80 very simple nature for the post body. 85

Therefore a very simple and efficient retaining means has been provided for a fence post of plastic nature which will reinforce the same and at the same time constitute means for retaining the keys in position 90 against any tendency of accidental displacement while the loops will engage with the keys to firmly hold the strands of wire against displacement. The device therefore, may be constructed at a minimum expense 95 and yet may be efficiently operated for supporting strands of a fence very easily and without danger of injury and with only a minimum chance of the strands being displaced when in use. 100

The foregoing description and accompanying drawing have reference to what might be considered to be the approved or preferred form of my invention. I desire it to be understood that I may make such 105 changes in the construction, combination and arrangement of parts, materials, dimensions, et cetera, as may prove expedient and fall within the scope of the appended claims.

Having thus fully described my invention what I claim as new and desire to secure by Letters Patent, is:—

1. A device of the character described comprising the combination of a plastic body having a centrally arranged longitudinally extending channel upon one face thereof and a strip of reinforcing wire mesh embedded therein adjacent the channeled face, a longitudinally extending key within the channel, said reinforcing strip having strands projecting into the channel and straddling the said key on all sides throughout its length whereby the latter is held in centrally spaced relation to the walls of the channel and substantially flush with the outer face of the body, and binding means connecting the key and straddling strands at intervals and providing means for binding a transverse fence wire in engagement with said key. 110 115 120 125 130

2. A device of the character described comprising a post having a semi-circular channel extending longitudinally of one face, a key wire, a wire mesh embedded in the post adjacent the channeled-face and having strands projecting centrally into, and intertwisting throughout the length of the channel to provide aligned coils or spiral loops into which the said key is adapted to be inserted, said loops holding the key flush

with the channeled face of the post, and fence-tie means embracing the key and the key-encircling loops at intervals to lock them against relative displacement.

In testimony whereof I affix my signature 15 in presence of two witnesses.

ORAN OLSON.
